UNITED STATES PATENT OFFICE.

ERNEST L. GALE, SR., OF YONKERS, NEW YORK, ASSIGNOR TO OTIS ELEVATOR COMPANY, OF JERSEY CITY, NEW JERSEY, A CORPORATION OF NEW JERSEY.

ELECTRICAL CONTROLLING APPARATUS.

1,089,921.

Specification of Letters Patent. Patented Mar. 10, 1914.

Application filed May 2, 1912. Serial No. 694,646.

To all whom it may concern:

Be it known that I, ERNEST L. GALE, Sr., a citizen of the United States, residing at Yonkers, in the county of Westchester and State of New York, have invented a new and useful Improvement in Electrical Controlling Apparatus, of which the following is a specification.

My invention relates to alternating current electrical apparatus and more particularly to means for insuring the demagnetization of an alternating current brake magnet and operation of the brake as the current supply is cut off.

15 The invention herein is used in connection with an electric elevator although it may have a more general application.

A serious objection to the use of alternating current brakes for elevators and other apparatus is due to residual magnetism which, when the current supply is cut off, is sometimes sufficient to prevent the operation of the brakes. This has frequently resulted in serious accidents.

25 An object of the present invention is to overcome this objection by providing means that will insure the demagnetization of the brake magnet. The amount of residual magnetism in an alternating current magnet 30 depends largely on the particular phase of the current at the instant the circuit is opened. The magnetism rapidly fluctuates between maximum value and zero owing to the current alternations. If the circuit is 35 opened when the magnetic flux is at or near zero, there will of course be little or no residual magnetism; but if the circuit is opened while the magnetic flux is large, the residual magnetism will be considerable.

40 In accordance with my invention, I provide means for momentarily introducing a high resistance in the brake magnet circuits, just before the circuits are opened. This permits a very small alternating current to 45 flow momentarily, which is sufficient to overcome any residual magnetism, and thus insure the release of the magnet cores or armatures and the application of the brake.

The present invention may be considered 50 a modification of the invention set forth in my co-pending application for patent on a brake magnet demagnetizing device, Serial No. 571,899, filed July 14, 1910.

In the accompanying drawings, Figure 1

is a diagrammatic view of an elevator system 55 embodying my invention; Fig. 2 is a diagrammatic view showing the arrangement of the brake coils; Fig. 3 shows a modification of the arrangement disclosed in Fig. 1, the brake coils all being connected in series 60 with the resistance; Figs. 4 and 5 show further modifications of the arrangement disclosed in Fig. 1.

The elevator system disclosed in Fig. 1 is not new except as it involves a resistance and 65 controlling circuits therefor in connection with the brake mechanism. A brief description of the general arrangement will therefore suffice: A multi-phase system is shown in which current is supplied through the 70 main wires 1, 2 and 3, which lead through a main line switch 4 to the potential switch P, reversing switches R, R' and motor M. On the motor shaft is a traction sheave or hoisting drum D on which run the cables 5 connected to the car C and counterweight W. An alternating current brake B, which may 75 be of usual construction, is provided, and comprises brake magnet coils a, a', b, b', as shown in Fig. 2. A starting resistance Y is 80 connected in the rotor circuit of the motor, said resistance being controlled by a series of accelerating magnets c, d, e, f. A controller K preferably located in the car controls the circuits for the reversing switch 85 magnets and the accelerating magnets, and thereby controls the normal operation of the car. If the lever 6 of the car controller K is moved for example to the right, a circuit for the magnet coil of the reversing switch R is 90 established which may be traced as follows: From the main wire 3 through conductor 7, coil 8 of the reversing switch R, conductor 9, contacts 10, 11, 12 of the car switch, conductors 13 and 14 to the main wire 2. The magnet 95 8 being energized the reversing switch R is operated to a closed position and thereby establishes a circuit for the magnet coil of the potential switch P. This circuit may be traced from the main wire 3, through conductor 15 and contacts 16 of the reversing switch R, conductor 17, magnet coil 18 of the potential switch, conductor 19, slack cable switch 20, speed governor switch 21, upper car limit switch 22, emergency switch 23 in 100 the car, conductor 24, lower limit switch 25, and conductor 14, to the main wire 2. The magnet 18 being thus energized, closes the

potential switch P and thereby completes the circuits for the stator of the motor. These circuits are as follows: The conductor 1 is connected through contacts 26, conductor 27, contacts 28, and conductor 29 with one terminal of the motor. The main wire 3 is likewise connected through potential switch contacts 30, conductor 31, contacts 32 of the reversing switch R, and conductor 33 to another terminal of the motor. The main wire 2 is connected directly to the motor independently of the potential and reversing switches. The motor M therefore receives a starting current. The brake magnets are also energized as will be more fully set forth hereinafter, and the brake lifted to permit the motor to start. The motor starts and runs at slow speed with a starting resistance Y in the rotor circuit. The operation of the car switch lever 6 as above noted permits the cam block 35 to move downward, such movement being preferably retarded by a dashpot or other suitable means. This cam block permits the switches 36, 37, 38 and 39 to close in succession and thereby successively energize the magnets c, d, e and f. The circuit through the switch 36 for example may be traced as follows: From the main wire 2, through conductor 14, switch 36, conductor 40, coil of magnet c, conductor 29, reversing switch contacts 28, conductor 27, potential switch contacts 26, to the main wire 1. The magnet c being energized closes its switch and short-circuits the first sections of the resistance Y, thereby permitting an increase in the speed of the motor. The magnets d, e and f, are likewise operated in turn to short-circuit the remainder of the starting resistance in a series of steps, and thus gradually bring the motor up to full speed.

When the reversing switch and potential switch were closed as above noted, circuits for the brake magnet coils were established as follows: From the conductor 1, through potential switch contacts 26, conductor 41, brake magnet coils a, a', conductor 42, contacts 43 and 44 on the reversing switch R, and from thence to the main wire 2. The brake coils b, b', likewise receive current through a circuit including the main wire 3, potential switch contacts 30, conductor 45, magnet coils b, b', conductor 46, reversing switch contacts 43 and 44, and main wire 2. Between the conductors 42 and 46 is connected a resistance X, comprising sections x and x'. At the junction of said sections is connected a conductor 47 which leads directly to the main wire 2 independently of the reversing switches. The purpose of the resistance X and conductor 47 is to permit a small momentary current through the brake magnet to insure its demagnetization when the reversing switches are opened as will presently be described.

To stop the motor and car, the controller

switch 6 is brought back to central position, thereby opening the switches 36, 37, 38 and 39, to cause the starting resistance Y to be reinserted, and also to break the reversing switch magnet circuit at the contacts 10, 12. 70 The reversing switch magnet being deenergized, the switch R opens, and cuts off the current supply to the motor. The opening of the switch R also breaks the circuit through the magnet 18 of the potential 75 switch so that the latter is also opened. It should be here noted that a slight period of time elapses between the opening of the reversing switch and the potential switch, which time, however, I have found sufficient 80 to accomplish the purpose of the present invention. When the reversing switch opens, the circuits for the magnet coils as above traced through the reversing switch contacts 43, 44, are opened, but a small demagnetizing current is still allowed to flow temporarily through the resistance X. That is the circuit through the magnet coils a, a' is completed by way of conductor 42, resistance x' and conductor 47. The circuit for 85 the coils b and b' is likewise completed through conductor 46, resistance x and conductor 47. The resistances x, x' are high, so that only a very small alternating current is permitted through the magnet coils. 90 This current, however, is sufficient to overcome any residual magnetism in the brake magnets, completely demagnetizing the latter and insuring the brake being lifted. Without this resistance, the brake magnet 100 circuits might be opened at an instant when there was a large magnetic flux through the magnet, which would permit a high residual magnetism which might be sufficient to prevent the brake being lifted. With the 105 present invention, the small fluctuating current with the resistance in the circuits overcomes any such residual magnetism. The opening of the potential switch opens the brake circuits, but the slight time elapsing 110 between the opening of the reversing switch and potential switch is sufficient to permit the resistance X to accomplish its purpose.

Fig 3 shows a modified arrangement in which the conductor 47 of Fig. 1 leading from the resistance X is omitted. With this arrangement it will be seen that between the opening of the reversing switch and the potential switch the brake magnet coils are connected in series through the resistance X. 115 The circuit may be traced as follows: From the main 1, through contacts 26, conductor 41, brake coils a, a', the resistance X, brake coils b', b, conductor 45 and contacts 30, main wire 3. The principle of operation is 120 the same as already described in connection with Fig. 1.

Fig. 4 shows a further modification in which the brake circuit contacts 43 and 44 of the reversing switches are omitted. The 130

brake magnet in this instance comprises two single phase coils a'' , b'' . When the potential and reversing switches are closed, the brake coils receive current by way of the reversing switch contacts 28, 32. When the reversing switch R is opened in stopping the motor, resistances X are momentarily introduced into the brake magnet circuits, until the potential switch P opens.

10 Fig. 5 illustrates another modification in which each of the brake coils a'' , and b'' is normally connected across two of the mains while the motor is receiving current. One terminal of the coil a'' is connected 15 through conductor 41, and the potential switch to the main wire 1. One terminal of the coil b'' is likewise connected through conductor 45 to the main wire 3. The opposite terminals of said coils are connected 20 together and through the common wire 50, contacts 51 of the reversing switch, and wire 52 to the main wire 2. It will thus be seen that each of the brake coils is directly across two of the main wires and receives a single 25 phase current. When the reversing switch R is opened, the circuit through the common wire 50 is broken at the contacts 51. This leaves the brake coils momentarily in series 30 across the mains 1 and 3, until the potential switch opens to cut off all current supply to the brake coils. The coils being thus temporarily connected in series, the current therethrough and consequently the magnetic 35 flux is materially reduced, with a consequent diminution of the residual magnetism when the circuit is opened.

The operation when the car switch has been moved to the left is substantially the same as above described in connection with 40 the lever being moved to the right, except that the reversing switch R' will be operated and the phase relation changed to cause the motor to operate in a reverse direction. It will be understood of course that although 45 I have shown my invention applied to a multiphase system it is equally applicable to a system employing a single phase current.

I wish not to be limited to the particular 50 construction and arrangement shown, as various modifications might be made within the scope of the invention.

What I claim as new and desire to secure by Letters Patent of the United States is:—
55 1. In electrical controlling apparatus, the combination of a brake, a brake magnet, means to connect and disconnect said magnet to and from a source of alternating current supply, and means operable independent of the operation of the brake automatically to momentarily increase the resistance of the magnet circuit before it is disconnected from the said source of current supply.

60 2. In electrical controlling apparatus, the

combination of a motor, an electromagnetic brake, circuit controlling devices operable in succession to connect and disconnect the motor to and from a source of current supply, a brake magnet circuit controlled by 70 said devices, and means automatically to reduce the current through the brake magnet during the interval between the successive operation of said devices.

3. In electrical controlling apparatus, the 75 combination of an electrical circuit, switches in series in said circuit, means to effect the successive operation of said switches, an electromagnet, a circuit therefor controlled by said switches, and means automatically 80 to reduce the current through said magnet during the interval between the operation of said switches.

4. The combination of an electric motor, 85 switches operable in succession to establish a circuit for the motor, means to effect the opening of said switches in succession to open the motor circuit, an electromagnetic brake having its circuit controlled by said switches, and means automatically to reduce 90 the current in the brake magnet during the interval between the opening of said switches.

5. The combination of an electric motor, 95 reversing switches therefor, an additional switch in circuit with the reversing switches, means to effect the successive operation of said switches, an electromagnetic brake having its circuit controlled by said switches, and means automatically to modify the 100 brake circuit and thereby reduce the current in the brake magnet in the interval of time between the operation of said switches.

6. The combination of an alternating current electric motor, reversing switches 105 therefor, an additional switch in circuit with the reversing switches, an electro-magnetic brake having a circuit connected through a reversing switch and said additional switch to a source of current supply, a resistance, and circuit connections from the brake magnet through a reversing switch and said resistance to the source of current supply independent of said additional switch.

7. The combination of an alternating current motor, reversing switches therefor, a potential switch between the reversing switches and the current supply mains, an electro-magnetic brake, switch contacts in 120 the brake magnet circuit, and connected to be operated by a reversing switch to complete the brake magnet circuit therethrough and through the potential switch, resistances, and circuit connections to complete a brake 125 magnet circuit through said resistance and the potential switch independently of the reversing switches when the brake is in released position.

8. The combination of an alternating cur-

rent electric motor, reversing switches therefor, an electromagnetic main line switch in circuit with the reversing switches and having the circuit of its magnet extending through the reversing switches, an electromagnetic brake having its circuit extending through the reversing switches, and means to establish a modified circuit for the brake magnet during the interval of time between the operation of the said switches.

9. The combination of an alternating current electric motor, reversing and potential switches controlling the motor circuits, an electromagnetic brake, and means controlled by said switches to temporarily reduce the brake magnet current when said switches are operated to open the motor circuits and the brake is in released position.

10. The combination of an alternating current motor, reversing switches therefor, an electromagnetic brake, a resistance, and means associated with the reversing switches for automatically introducing said resistance momentarily in the brake circuit when a reversing switch is operated to open the motor circuit and the brake is in released position.

11. The combination of an electric motor, a switch controlling the motor circuit, an electromagnetic brake, and means associated with said switch and controlled thereby automatically to modify the brake circuit and reduce the current therethrough momentarily when said switch is operated to open

the motor circuit and the brake is in released position.

12. The combination of an alternating current electric motor, reversing switches therefor, an electromagnetic switch between the reversing switches and a source of current supply, an electromagnetic brake, circuit connections leading from the said electromagnetic switch to the brake magnet, brake circuit contacts carried by the reversing switches, return wires leading from the brake magnet through said contacts to the source of current supply, a resistance connected between said return wires and the circuit connections from said resistance to the source of current supply independent of the reversing switches.

13. The combination of an alternating current motor, a main line switch adapted to connect the motor to a source of current supply, an electromagnetic brake, a circuit therefor through said switch, resistance in the brake magnet circuit, a reversing switch, and means operable thereby to short-circuit said resistance and to include said resistance in the brake magnet circuit when the brake is in released position.

In testimony whereof, I have signed my name to this specification in the presence of two subscribing witnesses.
